UNITED STATES PATENT OFFICE

ALLEN L. SHIRLEY, OF PANHANDLE, TEXAS

DESIGN FOR A GRIP FOR GEAR-SHIFT LEVERS FOR AUTOMOBILES

Application filed May 1, 1929. Serial No. 31,065. Term of patent 3½ years.

To all whom it may concern:

Be it known that I, ALLEN L. SHIRLEY, a citizen of the United States, residing at Panhandle, in the county of Carson and State of Texas, have invented a new, original, and ornamental Design for Grip for Gear-Shift Levers for Automobiles, of which the following is a specification, reference being had to the accompanying drawing, forming a part thereof.

Figure 1 is a side elevational view of my improved invention; and

Figure 2 is a top plan view.

I claim:

The ornamental design for a grip for gear-shift levers for automobiles, as shown.

ALLEN L. SHIRLEY
